UNITED STATES PATENT OFFICE.

ROBERT D. RADCLIFFE, OF NEW YORK, N. Y., ASSIGNOR OF ONE-HALF TO
HANS S. BEATTIE, OF SAME PLACE.

METHOD OF CONSTRUCTING UNDERGROUND CONDUITS.

SPECIFICATION forming part of Letters Patent No. 440,576, dated November 11, 1890.

Application filed March 7, 1890. Serial No. 343,035. (No model.)

To all whom it may concern:

Be it known that I, ROBERT D. RADCLIFFE, a citizen of the United States, residing at New York, in the county and State of New York, have made a new and useful invention in the art of building or constructing subways, tunnels, sewers, or analogous structures located beneath streets, roads, or public passage-ways, of which the following is a specification.

10 The objects of my invention are, first, to diminish the expense incurred in the construction of such structures; second, to arrange during the paving or grading of a street for the future construction of a completed 15 tunnel, subway, sewer, or analogous structure; third, to insure more perfect workmanship in the building of such structures; fourth, to economize time in the construction of this type of structures by building them while the 20 street or roadway is being graded, paved, or completed; fifth, to admit of the construction of the top or roof portion of such structures from the surface of the street or roadway in such manner as to offer a minimum inconvenience to street or road traffic on a completed and occupied street or roadway. I 25 accomplish these objects by the practice of the method and the adaptation for use of the structure hereinafter described, but more 30 particularly pointed out in the claims which follow this specification.

For a full understanding of my invention reference is had to the accompanying drawings, in which—

35 Figure 1 is a cross-sectional view of a paved or completed street or roadway having beneath it an arch, roof, or top of a tunnel built in accordance with my improved method. Fig. 2 is a sectional and partly perspective 40 view of a paved or completed street or roadway and a completed tunnel made in accordance with my invention.

45 My novel method of construction consists in building or completing the arch roof or top of a tunnel or subway at the same time that the street or roadway is graded, paved, or repaired and in providing this arch, top, or roof with side supports, under which the said walls of the tunnel may be built at leisure,

or when it is deemed necessary to complete 50 the entire structure.

Referring to the drawings in detail, C represents an arch built beneath the street or road surface and resting on side supports B of blue-stone or other substantial imperishable material having the desired strength to support the roof or arch. The excavated earth D is restored to place between the side walls a of the excavated surface trench on top of the arch after it is completed and has been 60 concreted at its base, as shown. The street-pavement is laid in place, as shown, and the arch-former (not shown) drawn forward, leaving the free archway A. In this way the arch is completed and left, as shown in Fig. 1, until it is desired to complete the entire tunnel. 65

When the tunnel is to be completed, I commence, preferably, at one end and excavate to the necessary distance under the free ends of the arch-supports B to admit the timber F and 70 continue the excavation at this width until I am enabled to brace or sustain the free ends of said arch-supports B on each side by timbers F and shoring-braces G, sufficient space being left between the feet of the braces on 75 opposite sides to permit the passage of dirt-cars in excavating. The excavation is continued to a sufficient side depth under the supports B to admit of the building of the side walls D, the floor E having first been constructed of cement, concrete, stone, or any of the usual types of tunnel-flooring before the shoring-braces are placed in position; or this order of construction may be varied at 80 will, as will suggest itself to the engineer, the 85 essential feature being the securing of the ends of the arch pending the building of the walls D. When the walls D are finally completed, the shoring and bracing timbers F G are removed, and the tunnel is ready for use. 90

In the drawings the arch and walls are shown as of brick, and the side supports are of blue-stone slabs of sufficient length and breadth to sustain the arch in sections; but it is obvious that any of the well-known substitutes for brick and stone may be used in the entire structure, such matters being within the skill of the artisan. 95

During the building of the arch, roof, or top C man-holes H (shown in dotted lines in Fig. 2) or ventilation-passages may be constructed where desired. In the same manner 5 branch arches running beneath side streets, alleys, or into the basements of houses on either side may be constructed, thereby forming a net-work of unfinished tunnels or subways beneath a city, to be completed at will 10 in the future.

I do not limit myself in the practice of my improved method to the construction of arches alone, as it is obvious that any top covering or roof of sufficient strength to support the 15 street traffic at all times may supplant the arch, the essential feature of my invention being that said roof, top, or support shall have means for sustaining it and its supported load while the side walls of the actual tunnel 20 are being put in place.

My improved method may also be practiced beneath streets already completed by simply opening a short length of pavement of the desired width and closing it again as the 25 work proceeds, while the tunnel beneath the arch or roof may be constructed at the pleasure of the builder with speed and security against accidents and at a minimum cost.

Having thus described my invention, what 30 I claim, and desire to secure by Letters Patent of the United States, is—

1. The described method of constructing a tunnel, subway, or analogous structure, consisting in excavating from the surface of the earth to a sufficient depth to build or place the roof, top, or arch of the structure, then building such roof, top, or arch, then sustaining it from below, and finally completing the entire structure from its interior, substantially as described.

2. The described method of constructing a subterraneous passage-way, which consists in excavating from the surface of the earth to a sufficient depth for the top, roof, or arch of the structure only, then placing said top, roof, or arch in position, and finally completing the structure by excavating from beneath the

top, roof, or arch and building its side walls in position to support the same, substantially as described.

3. The described method of constructing a subterraneous passage-way, consisting in excavating from the surface of the earth to the desired depth to conceal the top, roof, or arch of the structure, then excavating the passage-way beneath the top, roof, or arch, and then building the side walls in place, substantially as described.

4. The described method of providing ready means for subterraneous passage-ways beneath streets or roadways, consisting in building the roofs, tops, or arches only of the passage-ways when the streets are graded, paved, constructed, or repaired, substantially as described.

5. The described method of constructing subterraneous passages beneath the streets or roadways of a city, consisting in removing the paving or surface covering of the street or roadway, as the necessity of the case demands, then placing the roof, top, or arch of the structure in position, then restoring the street surface to normal condition, and finally completing the entire structure from below this roof, top, or arch, substantially as described.

6. The described method of constructing subterraneous passage-ways beneath streets or roadways, consisting in removing the street surface in such proportions of width and depth as the necessities of the case may demand, then placing the roof, top, or arch of the structure in position, then restoring the street or road to normal condition, then excavating the passage-way from the interior, then bracing or supporting the roof, top, or arch, and finally building the side walls under the ends of the roof, top, or arch, substantially as described.

ROBT. D. RADCLIFFE.
